LOCK

Charles B. Lowe, Stamford, Conn., assignor to
The Yale & Towne Mfg. Co., Stamford, Conn.,
a corporation of Connecticut

Application April 22, 1933, Serial No. 667,348

48 Claims. (Cl. 70—46)

This invention relates to locks, and especially locking cylinders of the sliding tumbler type, although it is equally applicable to pin tumbler or other types of cylinder locks.

5 Cylinder locks of any design may be attacked by the picking of the tumblers through the key hole. Another method involves the use of force, such as the insertion of a tool in the keyway and the forcible application of torque to that tool tending 10 to rotate the plug to shear the usual type of tumblers. It is the object of my invention to devise a cylinder lock of the type in which the application of force to the key plug, while sufficient to shear any resisting tumblers, will not be effective to unlock the mechanism controlled by the 15 cylinder.

More particularly, it is the object of my invention to devise a cylinder lock in which the tumblers of the lock must be set to permit free rotation of the plug relatively to the cylinder in order 20 that the cam mechanism operable by the plug may be effectively actuated, and where, if the plug is forcefully rotated, the cylinder securing means will give way to permit the plug and cylinder to rotate freely together.

It is a further object of the invention to devise a 25 cylinder lock in which the cam mechanism lies normally in a dead center position on the cylinder axis so that any forcible rotation of the cylinder that may be caused by the application of torque 30 to the plug thereof, will tend to rotate the cam mechanism in a dead center position, whereby it has no effective movement.

A still further object of the invention is to devise 35 a cylinder lock having a cam which lies normally out of the plane of the means which it is adapted to operate, it being movable into an effective operating plane by rotation of the key plug relatively to the cylinder.

It is also an object of my invention to devise a 40 locking cylinder which is readily insertable and removable from a lock mechanism, and whose removal is controlled by the rotation of the key plug in the usual manner by a predetermined key.

45 For a more detailed description of my invention, I shall refer to the drawings wherein Fig. 1 is a sectional view of a preferred modification of my cylinder lock as applied to a lock having switch mechanism therein. Fig. 2 is a view illustrating the action of the parts along the lines 2—2 of Fig. 1. Figs. 2A and 2B are views similar to Fig. 2 illustrating further positions occupied by the parts of Fig. 2. Fig. 3 is a view along the lines 3—3 of Fig. 1; Fig. 4 is a view along lines 4—4 of Fig. 1; 50 Figs. 5 and 6 are views along the lines 5—5 and

6—6 of Figs. 2 and 2B respectively. Fig. 7 is a view along the lines 7—7 of Fig. 6.

Fig. 8 is a sectional view of a second modification of my invention. Fig. 9 is a sectional view along the lines 9—9 of Fig. 8, while Fig. 10 is a view 5 along the lines 10—10 of Fig. 8. Figs. 11 and 11A are views taken along the lines 11—11 of Fig. 8, while Fig. 12 is a view taken along the lines 12—12 of Fig. 9.

Referring now more particularly to the drawings and especially Fig. 8, reference numeral 10 indicates a key plug adapted to rotate in the sleeve 11, which in turn is mounted in the lock housing 12. The sleeve 11 is used herein as the locking portion of my cylinder and will naturally take 15 different forms as dictated by the particular type of cylinder lock in which my invention may be embodied. Referring now to Figs. 9, 10, and 12, which show further parts of the invention, it is seen that the plug 10 has mounted therein a series 20 of tumblers 13 of the usual spring-pressed sliding tumbler type, which normally lock the plug to the sleeve 11 except when the tumblers are placed in a release position by a key as is readily understood by those skilled in the art.

The plug 10 has secured thereto an integral pin 14 which rides in a groove 15 in the plug sleeve 11 so as to limit the possible movement of the plug 10 relatively to the sleeve 11 and to retain it within the sleeve. A pin 16 is cast integrally with the 30 plug and is adapted to ride in the cutout portion 17 of a cam piece 18. This cam piece 18 is mounted for sliding movement on the bearing lugs 19 and 20 which are cast integrally with the sleeve 11. The cam piece 18 has an integral upstanding 35 lock operating cam post 21 which is adapted to cooperate with the bolt 22 as is illustrated in Fig. 8. This bolt 22 is merely shown diagrammatically since the pin 21 of the cam may operate any usual type of mechanism as is well understood 40 by those skilled in the art.

The sleeve 11 is maintained against any rotary movement within the housing 12 by cooperation of the pin 24 of the housing with the slot 25 in the sleeve. For preventing the outward movement 45 of the cylinder sleeve 11 from the housing 12 I prefer to utilize a spring member 26 shown best in Figs. 11 and 11A, which is adapted to lie in aligned grooves 28 and 27 of the cylinder sleeve 11 and the housing 12 respectively. The manner in which this retaining spring 26 is controlled will be indicated later. It will be well also to indicate that the pin 21 of the cam 18, in its locked position such as is illustrated in Figs. 8 and 9, is adapted to lie in a dead center position relatively 50

55

to the locking mechanism, which in this particular case happens to be the bolt 22. The object of this construction will also be indicated presently.

- 5 In the normal operation of the locking plug 10, a key is inserted into its keyway to operate the tumblers 13 and align them with the periphery of the plug. Rotation of the plug is then possible, and this rotation will cause the integral lug 16
10 of the plug to move the sliding cam member 18 on its bearings 19 and 20 so as to cause the pin 21 to retract the bolt 22, or to act similarly on any other type of locking mechanism which may be required.

15 The manner in which my lock will withstand attack will now be described. A tool or other mechanism may be inserted by force into the keyway of the plug 10 so that rotary force may be applied to the plug in the direction of the arrow 30 shown in Fig. 10, which torque will tend naturally to shear the tumblers 13. This torque will be transmitted through the tumblers 13 to the sleeve 11 and will be resisted by the pin 24 cooperating with the slot 25 of the cylinder sleeve.
20 This pin 24 is so designed that it is relatively weak as compared to the combined strength of the several tumblers 13. Therefore, this torque tending to shear the tumblers 13 will really shear the pin 24, and will naturally cause the free rotation
25 of the plug 10 with the sleeve 11. This free rotation of these parts, combined with the dead center relation of the pin 21 of cam 18, will simply cause the entire cam, sleeve and plug assembly to rotate as a unit, ineffective in every
30 respect to actuate the locking mechanism represented diagrammatically by the bolt 22.

35

Also, due to the fact that the plug 10 has a relatively large head which prevents any access to the sleeve 11, it is readily seen that any attempt to maintain the sleeve 11 in a fixed position while the plug 10 is rotated relatively to the sleeve 11, will be successfully resisted.

My entire plug and sleeve assembly is readily insertable in and out of the housing 12, thus making it possible to change the particular cylinder which may have been placed in said locking mechanism, whenever such change becomes desirable. The sleeve and plug are inserted into housing 12 with the slot 25 cooperating with the pin 24 to prevent later rotation of the sleeve relatively to the housing. Also, the spring member 26, upon reaching a point opposite the slot 27 of the housing 12, will spring into that slot to prevent endwise movement of the cylinder mechanism from the housing.

Preferably also, means are arranged to permit easy removal of the cylinder from the housing. The plug 10, as shown in Figs. 11 and 11A, has a notched portion 31 formed therein which cooperates with a hook end 32 of the spring 26 when the plug is rotated into the position of Fig. 11A. In that position, the downward depression of the spring 26 into the notched portion 31 is possible, as by a tool 33 inserted through the hole 34 of the housing member. It is quite obvious that rotation of the plug from the position of Fig. 11A will serve to wind up the spring member 26 so as to draw it entirely within the groove 28 of the cylinder sleeve 11, whereupon outward movement of the sleeve from the housing will be quite simple.

For the description of a further modification of my invention, I will now refer to Figs. 1 to 7 inclusive. In this modification, the relation of the plug 10 to the sleeve 11, and the method of

rotation of the plug 10 relatively to the sleeve 11 is identical with that of the modification shown in Fig. 8. However, in the modification of Fig. 1, I utilize a slide detent 35 operating in a groove 35 as shown in Fig. 7, to retain the plug in the sleeve 12, in place of the pin 14 and slot 15 connection shown in Fig. 8. In the main, however, my invention illustrated in Fig. 1 varies from the modification of Fig. 8 in that I utilize a cam mechanism which does not occupy a dead center 10 relation to the sleeve 11, but which in locked position occupies a position out of the plane of the locking mechanism which it is intended to operate. More particularly, the plug operated mechanism shown in Fig. 1 comprises the switch 15 block 36 which merely represents diagrammatically a locking mechanism which may be of any usual type. I shall now proceed to describe more in detail the cam operation of Fig. 1.

As is best shown in Figs. 1 and 3, the plug body 10 has an extension 37 having a cam groove 38 adapted to cooperate with the pin 39 of a lock operating cam member 40 in a manner which will be described presently. The plug 10 has a further extension 41 which cooperates further with the cam member 40 to support it in bearing relation to the plug. The cam member 40 has further bearing relation to the sleeve member 11, and is normally spring-pressed by the spring member 42 (Fig. 1) in a counter clockwise direction as viewed in Figs. 5 and 6. Also, the pin 39, one end of which has been indicated as resting in the cam slot 38 of the plug extension 37, has an upper end riding in a slot 43 of the sleeve member 11 as is best illustrated in Figs. 2, 2A, and 2B.

As will be readily understood, the spiral cam slot 38 tends, through the bottom portion of pin 39, to transmit movement to the cam member 40 in opposition to the spring 42. This movement of the cam member 40 is controlled by the co-action between the upper end of pin 39 and the L shaped slot 43 of the sleeve member 11. It will be well to indicate that in the position of Fig. 1, which is the locked position of the switch member 36, the controlling member 40 will be out of the plane of the slot 36a of the locking member 36 so that forceful rotation of the plug 10, which in turn will cause a forceful rotation of the sleeve 11 in the manner described with regard to modification of Fig. 8, will rotate the entire cylinder assembly relatively to the locking member 36 without affecting it in the slightest.

However, normal operation of the plug 10 by the alignment of its tumblers 13, will permit rotation of the plug relatively to the sleeve 11. This rotation will cause the cam groove 38 to cooperate with the bottom end of the pin 39 so as to cause a movement of the cam member 40 and its lugs 44 from the position of Fig. 2 to the position of Fig. 2A, and into the plane of the slot 36a of member 36. In the position of Fig. 2A, the pin 39 will have moved to the furthest end 38a of the slot 38. Further rotation of the plug 10 will cause the end 38a of the slot to actuate the pin 39, and this time the movement will be direct, causing the pin 39 to guide the locking cam from the position of Fig. 2A to the position of Fig. 2B. In this movement, the locking cam 40 and its lugs 44 will have moved to the position of Fig. 6 from the position of Fig. 5. Also, it will be quite obvious that the lugs 44 will have acted, through the slot 36a of the locking 75

member 36, to rotate that member in any manner which might have been desired.

Naturally, backward rotation of the plug 19 will first cause the portion 38a of the cam slot 33 to move the pin 39 and the locking cam member 40 attached thereto in a direction from Fig. 2B to Fig. 2A. Further movement of the plug 18 will cause movement of the pin 39 and its secured locking cam member back to the initial 10 position of Fig. 2 and out of the plane of the locking piece 36.

While I have thus described two modifications of my invention, it should be understood that I consider my contribution to the art to be 15 very broad, and that I do not wish to be limited in the monopoly which I may secure, except as may be required by the state of the art.

I claim:

1. In a cylinder lock, a locking cam, a key plug for operating said cam, tumblers for locking said plug against rotation except when said tumblers are properly positioned, controlling means forming a portion of said cylinder lock and movable by said plug when said plug is rotated forcibly without proper positioning of the tumblers so as to tend to shear said tumblers, and means whereby the locking cam of said cylinder lock is controlled by said controlling means so as to be inoperable by said plug when 25 said controlling means are moved by said forcible rotation of the plug without proper positioning of the tumblers.

2. In a cylinder lock, a locking cam, a key plug for operating said cam, tumblers for locking said plug against rotation except when said tumblers are properly positioned, controlling means forming a portion of said cylinder lock and actuatable by said plug when said plug is rotated forcibly without proper positioning of the tumblers so as 30 to tend to shear said tumblers, and means whereby the locking cam of said cylinder lock is controlled by said controlling means so as to be inoperable by said plug when said controlling means are actuated by said forcible rotation of the plug without proper positioning of the tumblers.

3. In a cylinder lock, a lock operating cam, a sleeve forming a portion of said cylinder lock, a key plug in the sleeve of said cylinder lock, 35 tumblers for locking said plug to the sleeve except when properly positioned by the key, means of connection whereby the operating cam is actuated by said key plug when the plug is properly released for rotation relatively to said sleeve and is rotated, and means for preventing effective operation of said cam when said plug is forcibly rotated without release of its tumblers in such manner as to rotate the sleeve therewith.

4. In a lock, a lock cylinder comprising a cylinder sleeve, a key plug in said sleeve, tumblers for locking it against rotation relatively to said sleeve except when said tumblers are properly positioned, a lock controlling cam mounted in said 40 lock cylinder and movable in a controlling manner by relative movement between said cylinder sleeve and key plug as permitted by proper positioning of the tumblers, means whereby said cylinder sleeve is so maintained in the lock that forcible rotation of the key plug without setting of the tumblers will rotate said cylinder sleeve integrally with the plug, whereby to prevent 45 forceful relative rotation between said plug and cylinder sleeve.

5. In a lock, a lock cylinder comprising a cylin-

der sleeve, a key plug in said sleeve, tumblers for locking said plug against rotation relatively to said sleeve except when said tumblers are properly positioned, a lock controlling cam, means whereby said cam is movable in a controlling manner by rotation of said plug relatively to said cylinder sleeve when said plug is released by proper positioning of the tumblers, means for maintaining the sleeve against rotation in said lock, said means being so constructed that forcible rotation 10 of the key plug without setting of the tumblers will rotate said sleeve integrally with the plug, and against the force of said holding means, whereby to prevent operation of said cam by 15 forceful relative rotation between said plug and cylinder sleeve.

6. In a lock, a lock cylinder comprising a cylinder sleeve, a key plug in said cylinder sleeve, tumblers for locking said plug against rotation relatively to said cylinder sleeve except when said 20 tumblers are properly positioned, a lock controlling cam mounted on said cylinder sleeve, means of connection between said plug and cam whereby rotation of said plug relatively to said sleeve will actuate said cam in a lock operating manner, 25 and means for holding said sleeve in said lock adapted to release said sleeve readily when said plug is forcibly rotated without release of the tumblers, whereby said plug, sleeve, and cam may rotate freely together without actuation of said cam in a lock operating manner.

7. In a lock, a lock cylinder comprising a cylinder sleeve, a key plug in said cylinder sleeve, tumblers for locking said plug against rotation 30 relatively to said cylinder sleeve except when said tumblers are properly positioned, a lock controlling cam having an operating portion normally positioned on the axis of said sleeve, means of connection between said plug and cam whereby rotation of said plug relatively to said sleeve 35 will actuate said cam in a lock operating manner, and means for holding said sleeve against rotation in said lock adapted to release said sleeve readily when said plug is forcibly rotated without release of the tumblers, whereby said plug, sleeve, 40 and cam may rotate freely together without actuation of said cam in a lock operating manner.

8. In a lock, a lock cylinder comprising a cylinder sleeve, a key plug in said cylinder sleeve and overlying the front end of the sleeve to prevent 50 access thereto, tumblers for locking said plug against rotation relatively to said sleeve except when said tumblers are properly positioned, a lock controlling cam mounted on said sleeve, means of connection between said plug and cam 55 whereby rotation of said plug relatively to said sleeve will actuate said cam, in a lock operating manner and means for holding said sleeve in said lock adapted to release said sleeve readily when said plug is forcibly rotated without release of 60 the tumblers, whereby said plug, sleeve, and cam may rotate freely together without actuation of said cam in a lock operating manner.

9. In a lock, a lock cylinder comprising a cylinder sleeve, a key plug in said cylinder sleeve, 65 tumblers for locking said plug against rotation relatively to said sleeve except when said tumblers are properly positioned, a lock controlling cam, means of connection between said plug and cam whereby rotation of said plug relatively to said 70 sleeve will actuate said cam in a lock operating manner, means for maintaining said cylinder sleeve against rotation in said lock, said means being relatively weaker than said tumblers and adapted to give way when said plug is forcibly 75

- rotated without release of the tumblers, whereby said plug, sleeve, and cam may rotate freely together without actuation of said cam in a lock operating manner.
- 5 10. In a lock, a lock cylinder comprising a cylinder sleeve, a key plug in said cylinder sleeve, tumblers for locking said plug against rotation relatively to said sleeve except when said tumblers are properly positioned, a lock controlling cam mounted on said cylinder sleeve, means of connection between said plug and cam whereby rotation of said plug relatively to said sleeve will actuate said cam in a lock operating manner, means for maintaining said cylinder sleeve against rotation in said lock, said means being relatively weaker than said tumblers and adapted to give way when said plug is forcibly rotated without release of the tumblers, whereby said plug, sleeve and cam may rotate freely together 10 without actuation of said cam in a lock operating manner.
- 15 11. In a lock, a lock cylinder comprising a cylinder sleeve, a key plug in said cylinder sleeve, tumblers for locking said plug against rotation relatively to said sleeve except when said tumblers are properly positioned, a lock controlling cam mounted normally in a dead center relationship to said sleeve, means of connection between said plug and cam whereby rotation of said plug relatively to said sleeve will actuate said cam and move it out of dead center position in a lock operating manner, and means for holding said sleeve in said lock adapted to release said sleeve readily when said plug is forcibly rotated without release 20 of the tumblers, whereby said plug, sleeve and cam may rotate freely together with said cam in dead center position.
- 25 12. In a lock, a lock cylinder comprising a cylinder sleeve, a key plug in said cylinder sleeve, tumblers for locking said plug against rotation relatively to said sleeve except when said tumblers are properly positioned, a lock controlling cam mounted on said cylinder sleeve and lying normally in a dead center relationship to said sleeve, means of connection between said plug and cam whereby rotation of said plug relatively to said sleeve will actuate said cam and move it out of dead center position in a lock operating direction, and means for holding said sleeve in said lock 30 adapted to release said sleeve readily when said plug is forcibly rotated without release of the tumblers, whereby said plug, sleeve and cam may rotate freely together with said cam in its dead center position.
- 35 13. In a lock, a lock cylinder comprising a cylinder sleeve, a key plug in said sleeve, tumblers for locking said plug against rotation relatively to said sleeve except when said tumblers are properly positioned, a lock controlling cam mounted 35 in said lock cylinder and normally lying out of its plane of effective controlling operation, means of connection between said plug and cam whereby rotation of said plug relatively to the sleeve will move said cam into its operating plane, and means for holding said sleeve in said lock adapted to release said sleeve readily when said plug is forcibly rotated without release of the tumblers, whereby said plug, sleeve and cam may rotate freely together without proper actuation of said cam into a lock controlling position.
- 40 14. In a lock, a locking cylinder comprising a sleeve and plug and tumblers adapted to interlock said sleeve and plug except when properly positioned by a key, a lock controlling cam carried by said sleeve and actuatable by said plug when key rotated relatively to said sleeve, said cam being mounted to lie out of its plane of controlling operation when in locked position so that free rotation of said sleeve and plug relatively to said lock will merely cause said cam to rotate idly 45 without any lock operating effect.
- 45 15. In a lock, a locking cylinder comprising a sleeve and plug and tumblers adapted to interlock said sleeve and plug except when properly positioned by a key, a lock controlling cam carried by said sleeve and actuatable by said plug when key rotated relatively to said sleeve, said cam being mounted to lie out of its plane of controlling operation when in locked position so that free rotation of said sleeve and plug relatively to said lock will merely cause said cam to rotate idly 50 without any lock operating effect, and means whereby rotation of said plug relatively to said sleeve first moves said cam into its plane of operation, and then rotates it to operate the lock.
- 55 16. In a lock, a locking cylinder comprising a sleeve and plug and tumblers adapted to interlock said sleeve and plug except when properly positioned by a key, a lock controlling cam carried by said sleeve and actuatable for lock operation by said plug when key rotated relatively to said sleeve, said cam being mounted in dead center relationship to the lock mechanism when in locked position so that free rotation of said sleeve and plug together relatively to said lock will merely cause said cam to rotate idly 55 without any lock operating effect.
- 60 17. In a lock, a locking cylinder comprising a sleeve and plug and tumblers adapted to interlock said sleeve and plug except when properly positioned by a key, a lock controlling cam actuatable for lock operation by said plug when key rotated relatively to said sleeve, said cam being mounted in dead center relationship to the lock mechanism when in locked position so that free rotation of said sleeve and plug together relatively to said lock will merely cause said cam to rotate idly 60 without any lock operating effect.
- 65 18. In a lock, a readily removable and insertable cylinder assembly comprising a cylindrical sleeve and a plug having tumblers for interlocking the sleeve and plug except when said tumblers are key set, and a cam operable by rotation of said key plug in said sleeve when said key plug is properly released, means cooperating between said sleeve and lock to prevent rotation of said sleeve when it has been properly inserted, and additional readily releasable means for preventing outward movement of said cylinder assembly from said lock.
- 70 19. In a lock, a readily removable and insertable cylinder assembly comprising a sleeve and plug having tumblers for interlocking the sleeve and plug except when said tumblers are key set, and a cam operable by rotation of said key plug in said cylinder assembly when said key plug is properly released, a pin and slot connection between said cylinder assembly and lock to prevent relative rotary movement, and a spring snap connection between said cylinder assembly and lock 65 to prevent outward movement of said cylinder assembly.
- 75 20. In a lock, a lock cylinder assembly for said lock comprising a sleeve and plug having tumblers for interlocking the sleeve and plug except when said tumblers are key set, and a cam operable by rotation of said key plug in said sleeve when said key plug is properly released, means cooperating between said sleeve and lock to prevent rotation of said sleeve in said lock, said rotation prevent-

ing means being weaker than said tumblers whereby forceful rotation of said plug will overcome said rotation preventing means so as to permit free rotary movement of the sleeve in said

5 lock.

21. In a lock, a lock cylinder assembly for said lock comprising a cylinder sleeve and plug having tumblers for interlocking the cylinder sleeve and plug except when said tumblers are key set, and a cam operable by rotation of said key plug in said cylinder sleeve when said key plug is properly released, a pin and slot connection between said cylinder sleeve and lock to prevent relative rotary movement, said pin and slot connection being weaker than said tumblers whereby forceful rotation of said plug will shear said pin and slot connection to permit full rotary movement of the cylinder sleeve in said lock.

22. In a lock, a readily removable and insertable lock cylinder assembly comprising a cylinder sleeve and plug having tumblers for interlocking the cylinder sleeve and plug except when said tumblers are key set, and a cam operable by rotation of said key plug in said cylinder sleeve when said key plug is properly released, releasable means for maintaining said cylinder sleeve in said lock, said releasable means being normally inoperable by said plug but movable into operable relation therewith in a predetermined position of the plug whereby the rotation of the plug from that position will withdraw said means from its cylinder sleeve retaining position.

23. In a lock, a readily removable and insertable lock cylinder assembly for said lock comprising a cylinder sleeve and plug having tumblers for interlocking the cylinder sleeve and plug except when said tumblers are key set, and a cam operable by rotation of said key plug in said cylinder sleeve when said key plug is properly released, said lock having a groove and spring retaining means carried by the cylinder sleeve and adapted to ride into said groove, means whereby said spring means may be operatively connected to the plug in a predetermined position of the plug, whereby rotation of the plug from that position will withdraw the spring means from retaining position.

24. In a lock, a readily removable and insertable lock cylinder assembly for said lock comprising a cylinder sleeve and plug having tumblers for interlocking the cylinder sleeve and plug except when said tumblers are key set, and a cam operable by rotation of said key plug in said cylinder sleeve when said key plug is properly released, said lock having a groove and a spring carried by said cylinder sleeve and operating in said groove to retain the cylinder sleeve in the lock, means of connection between the plug and spring whereby the spring can be moved into connection with the plug in a predetermined key rotated position of the plug for movement by the plug into a releasing position, said spring being movable into cooperation with the plug through a hole in said lock.

25. In a lock, a lock cylinder comprising a cylinder sleeve, a key plug in said sleeve, tumblers for locking said plug to said sleeve except when properly set by a key, means retaining said cylinder sleeve against rotation in said lock so that when the tumblers are properly set, the plug will rotate freely relatively to the stationary sleeve, a lock operating device, means whereby said device is actuated in a lock operating manner upon said relative movement of the sleeve and plug, said sleeve retaining means being weaker than said tumblers so that forceful rotation of the plug will overcome

said retaining means so that the plug and sleeve will rotate together so as to be ineffective thereafter to then actuate said lock operating device in a lock operating manner.

26. In a lock, a lock cylinder comprising a cylinder sleeve, a key plug in said sleeve, tumblers for locking said plug to said sleeve except when properly set by a key, stop means operable to prevent rotation of said sleeve in said lock whereby when said tumblers are key set, said plug will rotate relatively to the sleeve, said tumblers being relatively stronger than said stop means whereby forceful rotation of said plug without setting said tumblers will overcome said stop means.

27. In a lock, a locking cylinder comprising a cylinder sleeve and plug and tumblers adapted to interlock said sleeve and plug except when properly positioned by a key, a lock controlling cam carried by said sleeve and actuatable for lock operation by said plug when key rotated relatively to said sleeve, said cam being arranged to lie normally out of its lock operating plane, means whereby it is moved into its operating plane by the first movement of the plug relatively to the sleeve and then actuated for lock operation by further rotation of the plug relatively to the sleeve, whereby free rotation of said plug and sleeve together relatively to said lock will merely cause said cam to rotate idly without any lock operating effect.

28. In a lock, a locking cylinder comprising a cylinder sleeve and plug and tumblers adapted to interlock said sleeve and plug except when properly positioned by a key, a lock controlling cam carried by said sleeve and actuatable for lock operation by said plug when key rotated relatively to said sleeve, said cam being arranged to lie normally out of its lock operating plane, means whereby it is moved into its operating plane by the first movement of the plug relatively to the sleeve and then actuated for lock operation by further rotation of the plug relatively to the sleeve.

29. In a lock, a readily removable and insertable cylinder assembly comprising a cylindrical sleeve and a plug having tumblers for interlocking the cylindrical sleeve and plug except when said tumblers are key set, said cylindrical sleeve being mounted for rotation in said lock, means cooperating between said cylindrical sleeve and lock to prevent rotation of said cylindrical sleeve when it has been properly inserted, and additional readily releasable means for preventing outward movement of said cylindrical sleeve from said lock.

30. In a lock, a readily removable and insertable cylinder assembly comprising a sleeve and plug having tumblers for interlocking the sleeve and plug except when said tumblers are key set, a pin and slot connection between said cylinder assembly and lock to prevent relative rotary movement and a spring snap connection between said cylinder assembly and lock to prevent outward movement of said cylinder assembly.

31. In a lock, a lock cylinder assembly for said lock comprising a sleeve and plug having tumblers for interlocking the sleeve and plug except when said tumblers are key set, means cooperating between said sleeve and lock to prevent rotation of said sleeve in said lock, said rotation preventing means being weaker than said tumblers whereby forceful rotation of said plug will overcome said rotation preventing means so as to permit free rotary movement of the sleeve in said lock.

32. In a lock, a lock cylinder assembly for said lock comprising a cylinder sleeve and plug having tumblers for interlocking the cylinder sleeve

and plug except when said tumblers are key set, a pin and slot connection between said cylinder sleeve and lock to prevent relative rotary movement, said pin and slot connection being weaker than said tumblers whereby forceful rotation of said plug will shear said pin and slot connection to permit full rotary movement of the cylinder sleeve in said lock.

33. In a lock, a readily removable and insertable lock cylinder assembly comprising a cylinder sleeve and plug having tumblers for interlocking the cylinder sleeve and plug except when said tumblers are key set, releasable means for maintaining said cylinder sleeve in said lock, said releasable means being normally inoperable by said plug but movable into operable relation therewith in a predetermined position of the plug whereby the rotation of the plug from that position will withdraw said means from its cylinder sleeve retaining position.

34. In a lock, a readily removable and insertable lock cylinder assembly for said lock comprising a cylinder sleeve and plug having tumblers for interlocking the cylinder sleeve and plug except when said tumblers are key set, said lock having a groove and spring retaining means carried by the cylinder sleeve and adapted to ride into said groove, means whereby said spring means may be operatively connected to the plug in a predetermined position of the plug, whereby rotation of the plug from that position will withdraw the spring means from retaining position.

35. In a lock, a readily removable and insertable lock cylinder assembly for said lock comprising a cylinder sleeve and plug having tumblers for interlocking the cylinder sleeve and plug except when said tumblers are key set, said lock having a groove and a spring carried by said cylinder sleeve and operating in said groove to retain the cylinder sleeve in the lock, means of connection between the plug and spring whereby the spring can be moved into connection with the plug in a predetermined key rotated position of the plug for movement by the plug into a releasing position, said spring being movable into cooperation with the plug through a hole in said lock.

36. In a cylinder lock, a sleeve, a key plug, tumblers adapted to lock said key plug to said sleeve, a lock operating cam carried by said sleeve, a lock operating cam carried by said sleeve and slidably relatively thereto, and a cam carried by said plug adapted to operate said sleeve cam as said plug rotates relatively to said sleeve, said sleeve cam being normally positioned in a concentric position relatively to the axis of the sleeve so that rotation of said sleeve and plug together will not move said sleeve cam in a lock operating direction.

37. In a cylinder lock, a sleeve, a key plug, tumblers adapted to lock said plug to said sleeve except when said tumblers are properly set, a lock operating cam mounted in said sleeve for outward movement and then for rotary movement, and a connection between said cam and said plug whereby rotation of said plug will first move said cam on its mounting in an outward direction and will then rotate it, said cam when in its inward position being out of a lock operating plane so that rotation of said sleeve and plug together will not move said cam in a lock operating direction.

38. In a cylinder lock, a sleeve, a rotating key plug in said sleeve, tumblers adapted to lock said key plug to said sleeve in a predetermined position, a cam mounted for sliding movement on said sleeve and having an operating portion, means between said key plug and cam for sliding said

cam relatively to said sleeve, said cam being so positioned relatively to said sleeve when said plug is in its predetermined position that its operating portion is in dead center relation to the axis of said sleeve, whereby rotation of said sleeve and plug together will merely rotate the operating portion on the sleeve axis. 5

39. In a lock, a sleeve, a rotating key plug in said sleeve, tumblers adapted to lock said key plug to said sleeve in a predetermined position, 10 a cam mounted for sliding movement on said sleeve and having an operating portion, means between said key plug and cam for sliding said cam relatively to said sleeve, said cam being so positioned relatively to said sleeve when said plug is in its predetermined position that its operating portion is in dead center relation to the axis of said sleeve, whereby rotation of said sleeve and plug together will merely rotate the operating portion on the sleeve axis, means for maintaining said sleeve against rotation in said lock, said means being relatively weaker than said tumblers so that forceful rotation of said plug will overcome said means and will allow for free rotation of the cam and plug. 20

40. In a cylinder lock, a key plug, a cam, a guide for said cam, means between said guide and cam for guiding the cam for movement in a predetermined path having linear and rotary components with the linear component parallel 30 to the axis of said plug, and means of connection between said plug and cam for moving said cam in said path.

41. In a cylinder lock, a key plug, a cam member, a guide for said cam member, means of connection between said cam and said plug for actuating the cam upon rotation of the plug, and means whereby said guide acts to guide the cam for outward movement axially relatively to the plug and then for rotary movement when said 40 cam is actuated by said plug.

42. In a cylinder lock, a key plug, a cam, a guide for said cam, and a pin and slot connection between said plug and cam whereby said cam is moved by rotation of said plug, the said pin and 45 slot connection being effective to move said cam linearly and in a rotating path depending upon the construction of said guide means.

43. In a cylinder lock, a key plug, a cam, means of connection between said cam and plug 50 comprising a pin and spiral groove, said cam being rotatable with said plug through said pin and groove when said cam is maintained against endwise movement, said cam being movable endwise relatively to said plug through said pin and 55 groove connection when maintained against rotary movement.

44. In a cylinder lock, a key plug, a cam, means of connection between said cam and plug comprising a pin and spiral groove, said cam being 60 rotatable with said plug through said pin and groove when said cam is maintained against endwise movement while released for rotary movement, said cam being movable endwise relatively to said plug through said pin and groove connection when maintained against rotary movement, and guide means for determining the movement of said cam in a rotary and in an endwise direction when actuated by said plug. 70

45. In a cylinder lock, a key plug, a cam, a guide means, pin and slot connections between said cam and said guide means, on the one hand, and between said cam and said plug on the other hand, said connection between the plug and cam 75

being effective to move said cam by operation of the plug, said connection between the cam and guide means being effective to guide the cam in its movement.

5 46. In a cylinder lock, a key plug, a cam, a guide means, pin and slot connections between said cam and said guide means on the one hand, and between said cam and said plug on the other hand, said connection between the plug and cam 10 being constructed in the nature of a pin and spiral groove whereby said cam is movable endwise by said connection or is rotatable with said plug by said connection, said connection between the cam and guide being effective to guide the cam 15 for predetermined endwise and rotary movement relatively to said plug.

47. In a cylinder lock, a key plug, a cam, means of connection between said cam and plug comprising a pin and spiral groove, said cam being 20 rotatable with said plug through said pin and groove when said cam is maintained against endwise movement while released for rotary movement, said cam being movable endwise relative-

tively to said plug through said pin and groove connection when maintained against rotary movement but released for endwise movement, and guide means cooperable with said pin for determining the movement of said cam in a rotary 5 and in an endwise direction when actuated by said plug.

48. In a cylinder lock, a key plug, a cam means of connection between said cam and plug comprising a pin and spiral groove, said cam being 10 rotatable with said plug through said pin and groove when said cam is maintained against endwise movement while released for rotary movement, said cam being movable endwise relatively to said plug through said pin and groove connection when maintained against rotary movement but released for endwise movement, and guide means comprising a slot in said cylinder cooperable with said pin for determining the movement of said cam in a rotary and in an endwise direction 15 when actuated by said plug. 20
